UNITED STATES PATENT OFFICE

ROBERT H. KOENIG, OF HADDON HEIGHTS, NEW JERSEY

PROCESS OF FORMING GLASS TUBES FOR EYE-DROPPERS

Application filed March 19, 1932. Serial No. 599,990.

This invention relates to improvements in methods of forming glass tubes for eye-droppers.

The primary object of the present invention is to provide an improved method for forming the constricted end of an eye-dropper tube with a beaded tip without the necessity of piercing or otherwise puncturing the glass after the tip has been formed.

Another object of the invention is to provide an improved method for forming the dropper tubes with beads about their large ends.

A still further object of the invention is to provide a novel method of forming two dropper tubes together from a single piece of tubing stock and then separating a constricted central portion of the stock after forming beads about the constricted portion, in such a manner as to leave the constricted portions open and a bead about each which serves as a means of protecting the user of the tube against injury.

The invention will be best understood from a consideration of the following detailed description taken in connection with the accompanying drawing forming part of this specification, with the understanding, however, that the invention is not confined to any strict conformity with the showing of the drawing but may be changed or modified so long as such changes or modifications mark no material departure from the salient features of the invention as expressed in the appended claims.

In the drawing:—

Figure 1 is a view in side elevation of a piece of tubing stock, showing the manner of heating the end edges preparatory to the formation of beads thereon;

Figure 2 is a view of the tubing stock undergoing the second step in the process and showing the method of heating the central portion to facilitate drawing the same;

Figure 3 illustrates the third step of the method showing the manner of heating the central portion of the drawn part of the tube preparatory to forming the tip beads;

Figure 4 illustrates the fourth step showing how the tube is separated between the

tip beads to form the individual dropper tubes;

Figure 5 illustrates the dropper tubes after the completion of the step illustrated in Figure 4;

Figure 6 is a view in side elevation of a complete dropper tube.

Referring now more particularly to the drawing wherein like numerals of reference indicate corresponding parts throughout the several views, the numeral 1 indicates a section of glass tubing from which a pair of dropper tubes may be formed according to the present method. In carrying out the present method the section of tubing 1 is first heated about its end edges in any suitable manner, as for example, by rotating the tube with each of the edges in a flame 2 and when the end portions or edges of the tube are sufficiently softened longitudinal pressure is applied so as to spread the ends of the tube and thus form the beads 3 shown in Figure 2.

The second step in the present method consists in heating an area of the tube at a point midway between its ends by means of a plurality of flames 4 and when this central area has become sufficiently heated the tube is pulled from either end so as to draw out and constrict the central portion in the manner indicated at 5. There is thus obtained the elongated body comprising the two portions 6, each of which has an open end, and the elongated constricted central portion 5 connecting them together. These portions 6 each constitute the barrel of the finished dropper tube.

The next step in the present method is to apply heat through the medium of two flames, each of which is indicated by the numeral 7, or in any other suitable manner, to relatively close areas at the central part of the constricted portion 5, the body of the tube being meanwhile turned so as to form two relatively close rings of heat softened glass. After these two circular areas of softened glass have been formed by the flanges 7, pressure is applied to the ends of the tubular body to force the same toward one another and this results in the pressing outwardly of

the softened annular portions of the constricted part 5 to form the annular beads 8.

The two ends of the tubular body 1 are then connected with suitable air tubes and

8 air is forced into the body from each end and during this period a flame 9 or any other suitable heating means, is applied to the area of the constricted portion 5 between the beads 8 and the tube is melted through at this point.

10 Due to the pressure of air within the body of the tube the constricted portion between the beads 8 remains open as the glass between the beads is melted to allow the two sections 6 to be separated and thus there results the

15 two completed dropper tubes 10 each having the constricted tip portion terminating in one of the beads 8 and further having its end open and not requiring any further treatment before attaching the outer end which carries a bead 3 to the usual rubber cap (not shown), by means of which liquid is drawn into and expelled from the tube.

From the foregoing it will be readily apparent that by the foregoing method the 25 formation of dropper tubes is greatly expedited as it is unnecessary after the tube has been completed and the bead formed at the constricted end, to pierce or open the constricted end as is necessary in forming tubes 30 according to the methods at present followed.

It will, of course, be understood that the foregoing process may be carried out for the formation of the dropper tubes without beads at the constricted ends thereof, if desired.

35 In either case whether the beads are formed or not the same method of separating the two portions of the tube is followed and in carrying out this method the forcing of air into and through the dropper tubes is continued even after the tubes have been formed, so that a properly formed aperture at the constricted end of the tube will be obtained.

If the air injected into the ends of the connected dropper tubes should be cut off as 40 soon as the separation of the tubes is effected there is a possibility of the ends completely closing or closing to such a degree that the dropper tube will be practically useless.

Having thus described the invention, what 50 is claimed is:—

1. The herein described method of forming a pair of dropper tubes from a tubular body which consists in reducing the diameter of the body for a predetermined area midway between the ends thereof, then softening two relatively closely related circular areas about the reduced portion, then applying pressure to the two ends of the tubular body to force outwardly the softened areas 55 to form beads, and finally separating the tubular body between the beaded areas.

2. The method of forming a pair of dropper tubes from a single tubular glass body which consists in first heating the body 60 through a relatively wide area centrally,

then drawing out the central portion of the body to form a central constricted portion, then heating the central part of the constricted portion about two closely spaced annular areas, then applying pressure to the 70 ends of the body longitudinally thereof to spread the softened annular areas for the formation of outwardly extending surrounding beads, then melting out the portion of the restricted part of the body between the 75 said beads while maintaining an air pressure within the body to prevent the ends of the restricted portion adjacent the beads from closing during the melting process.

3. The herein described method of forming a pair of dropper tubes from a single tubular glass body which consists in heating the end edges of the body to soften the same, then applying longitudinal pressure to the ends of the body while in the softened 85 condition to force the softened portion outwardly for the formation of a surrounding bead, and then drawing out and constricting the central portion of the body and severing the same at the center of the constricted 90 portion.

4. The herein described method of forming a pair of dropper tubes from a tubular body which consists in reducing the diameter of the body for a predetermined area midway 95 between the ends thereof, then applying a narrow flame to the central part of the reduced portion, and coincident with the application of the narrow flame for the purpose of melting the center of the constricted portion, introducing air under pressure into the tubular body and continuing the discharge of air thereinto after the constricted portion has been severed and until the tips 100 have hardened.

In testimony whereof I hereunto affix my signature.
